UNITED STATES PATENT OFFICE.

RUDOLPH BECKER, OF ROSELLE PARK, NEW JERSEY, ASSIGNOR TO THE SINGER MANUFACTURING COMPANY, A CORPORATION OF NEW JERSEY.

HAT-SWEAT AND METHOD OF ATTACHMENT.

1,280,946.

Specification of Letters Patent.

Patented Oct. 8, 1918.

Application filed February 14, 1918. Serial No. 217,051.

To all whom it may concern:

Be it known that I, RUDOLPH BECKER, a citizen of the United States, residing at Roselle Park, in the county of Union and State of New Jersey, have invented certain new and useful Improvements in Hat-Sweats and Methods of Attachment, of which the following is a specification, reference being had therein to the accompanying drawings.

This invention relates to head coverings and particularly to sweat bands for straw hats and their method of attachment.

Heretofore in the sewing of sweat bands to straw hats by machine, as distinguished from hand sewing, it has been customary to fold a strip of cambric about a reed or wire and at or below the fold secure the lower edge of a leather sweat band by a zigzag or overseam. This produces what is known as the "hat sweat". The leather band of the "hat sweat" is then folded back over the overseam with the cambric substantially flat and the "hat sweat" thus prepared positioned within a hat with the cambric in approximately its final position and with the leather projecting in the opposite direction out from the bottom of the hat. The hat and sweat are then stitched together, the stitches penetrating the hat and cambric only and being located as close to the lower edge of the leather as the fold therein will permit. Then the leather is turned back into the hat. In the usual practice it is impracticable to get much closer than one-eighth of an inch from the lower edge of the leather without marring it by penetration of its fold with the needle. The "hat sweats" prepared as above described are sometimes made in exact lengths and their opposite ends secured together before being sewed in and sometimes are made approximately to length. In the former case they are said to be "fitted" to size and in the latter case "unfitted". The fitted "hat sweats" seldom conform precisely to the inner periphery of the rim of the hats to which they are sewn, generally being either a little too large or a little too small. If the "hat sweat" is too large the operator cannot distribute the surplus uniformly about the hat in sewing it in, because of its folded condition, and in the finished hat the sweat band presents an uneven appearance. On the other hand when the "hat sweat" is too

small its lower edge will stand away from the inner periphery of the brim, because it is not stitched at the lower edge of the leather directly to the hat, and in the finished hat the sweat band presents an unsightly appearance accentuated by the rounding away at the brim and crown junction.

When the "hat sweats" are sewn in unfitted to size, all the variations in size in the blocked hat are retained and exist in the finished hat. And unless the work is done carefully the lower edge of the leather will stand away from the brim because of the frictional resistance offered by the leather to the feed. Usually there is an excess length which is cut off.

In the present invention a soft edge of needle penetrable material is secured in a substantially fixed position to the rounded edge of the brim and crown junction and subsequently the leather sweat is stitched at its lower edge thereto. The principle of the present invention is to provide a straw hat with a soft edge so as to reproduce at the inner edge of the brim the condition of a soft or felt hat and then to sew the leather to the soft edge in substantially the same fashion as it is sewn to the inner periphery of a soft or felt hat at the present day.

In the prevailing practice the essential steps have been first the stitching of a leather sweat band to an anchoring member or strip and second the securing preferably by stitches of the anchoring member or strip only to the hat crown as close as possible to its junction with the brim. In the present invention substantially the same essential steps are pursued in the reverse order.

The object of this invention has been to improve the process of attaching sweat bands to straw hats and to better the character of the product.

More specifically it aims to produce a straw hat having a sweat band attached thereto secure against separation from the body of the hat and in such fashion that no gap occurs between the lower edge of the leather sweat band and straw braid of the body.

It also aims to produce a hat having an ornamental seam or seams securing the lower edge of the leather in place which seam or seams are regular in appearance and are not marred or detracted from by interlacing or interengaging with each other. It also

seeks to improve the existing methods of attaching sweat bands to straw hats by permitting performance of the operations or successive steps thereof, in whole as well as 5 in part, on a sewing machine and by permitting manufacturers to produce at a reasonable cost hats having sweat bands uniformly true to size.

The invention is illustrated in the accompanying drawings, in which Figure 1 shows a hat in perspective broken away in part to disclose a sweat band and anchoring member or strip. Figs. 2, 3 and 4 show diagrammatically successive steps in a preferred method of production. Fig. 5 shows on a larger scale a cross section through the junction of the brim and crown of the preferred form of construction. Figs. 6, 7 and 8 show diagrammatically successive steps in 15 the same method of production with a different form of anchoring member or strip for furnishing the soft edge to which the leather sweat band is seamed. Figs. 9 and 20 show other forms of an anchoring member or strip corded to thicken the soft edge. 25 And Figs. 11, 12 and 13 show a machine for making a finishing seam which is visible in the completed hat.

The preferred form of hat is illustrated in Fig. 1. It comprises a crown 1 and a brim 2 constructed in any suitable well known manner. To the junction 3 of the crown and brim portions an anchoring member in the form of a strip of needle penetrable material 4 is secured by a succession of keyed thread-loop structures 5 disposed at an angle to the crown of the hat and preferably at an angle of about 45° or more. More than half of the thread of seam 5 lies between the planes defined by the upper and lower surfaces of the hat brim as clearly shown in Fig. 5. The attachment of the strip 4 to the hat body is performed with the strip in the flat condition illustrated in Fig. 2, a portion 6 of the width of the strip throughout its length projecting outwardly from within the crown of the hat and a similar portion 7 lying within the crown in a substantially parallel relation with the vertical wall of the crown. The strip 4 is then folded within the hat and about the seam 5 as a hinge thus forming inner and outer layers 7 and 6 respectively of overlapping material. If desired the upper ends of the strip 4 as thus disposed within the hat may be secured in some suitable manner as by the stitches 8 indicated in Fig. 3. In the manner above described a fold 9, constituting a soft edge or ridge of needle penetrable material 50 is substantially fixed in position at the junction of the brim and crown.

A sweat-band 10, usually of leather, is then positioned within the hat in about the position it occupies when the hat is finished 55 and secured by a nice appearing seam 11 to

the soft edge or ridge 9 of the anchoring member or strip 4.

The successive steps pursued in the above described method are indicated diagrammatically in Figs. 2, 3 and 4 and the product 70 on an enlarged scale is clearly shown in Fig. 5. In Figs. 6, 7 and 8 substantially the same operations are performed in the same sequence, the anchoring member being in the form of a strip 14 an edge of which 75 has been hemmed or rolled or otherwise formed as indicated at 15 to define the soft edge or ridge to which the lower edge of the leather sweat-band is preferably over-seamed. 80

Obviously the soft edge or ridge to which the leather sweat-band is secured may be formed in a variety of ways and in Figs. 9 and 10 I have indicated how a cord 12 for instance may be employed to increase its 85 size.

The foregoing description relates to the method as it is employed for attaching sweat-bands to hat bodies whose rims are entirely integral with the crown of the hat being made by stitching straw braid in increasingly large spirals outwardly from the center or "button" of the hat crown. A large number of straw hats, however, have what is known as an under brim which is 95 made by stitching straw braid in the same manner but separately from the brim of the crown member. In such hats the separately formed upper and under brims are usually united together by stitching the outer edges 100 of the upper and under brims together. In securing a soft edge or ridge of penetrable material at the junction of the brim and crown of this class of straw hats the method of this application may be followed but a 105 specifically different method is preferable and it is fully disclosed in my contemporaneously filed application Serial No. 217,052.

It is to be distinctly understood, however, that this application is intended to cover the 110 broad common invention disclosed in both applications to wit: the provision of a straw hat with a soft edge or ridge of material substantially fixed in position at the junction of the brim and crown for the subsequent stitching of a leather sweat-band thereto at its lower edge.

Bearing in mind that this invention in its broadest scope is considered to include first the securing in any suitable manner of a soft 120 edge or ridge of material in substantially fixed position at the junction of the brim and crown of a straw hat and subsequently the stitching of a leather sweat by its lower edge to the soft edge or ridge, it will be 125 obvious that the subordinate steps of securing the anchoring member in place and then folding it to form the soft edge might be performed in the reverse order as indicated in Figs. 6-8 inclusive and advantages 130

of the invention realized. Various changes may in fact be made without departing from the spirit of my invention in its broadest aspect. The anchoring member, for instance may be attached to the hat body during the formation of the hat when the straw braid is being sewn in spirals or it may be secured in place by adhesives.

It is to be understood, however, that this invention does not comprehend within its scope the stitching of a leather sweat-band to a straw hat largely or entirely by hand as it is primarily intended to approximate in some respects and better in other respects a hand-stitched sweat-band. Hand stitched sweats are found only on the better grade of hats, being costly. Owing to the limited number of operatives who are capable of performing the hand stitching operation in a satisfactory manner and at a sufficiently rapid pace to earn enough per diem to live on, it is desirable, if not absolutely necessary, to supplant or supplement the work of these hand stitching operatives with a machine. This invention it is believed will commend itself to a large percentage of the straw hat trade because of the uniformity of the product, its comparatively low cost of production, and the finished appearance of the sweat-band in the completed hat.

It has been the common practice to provide a bell-shaped flare at the lower edge of the sweat-band so that the leather extends inwardly and upwardly away from the junction of the crown and brim. This has been done primarily to conceal some of the defects of the existing method of machine stitching leather sweats in place. In this invention this bell-shaped flare or flanging of the leather sweat is utilized to insure a uniformity in hats of a given size. As before indicated the hats of a given size, size seven for instance, are not of the same peripheral length at the junction of the brim and crown. Their peripheral length at this point varies from a quarter to a half of an inch. With this invention sized sweat-bands may be stitched first across the meeting ends of the leather and, if they be too small, distended by manipulation at their lower edges. If they be too large, the fullness of the lower edge of the leather may be distributed throughout the periphery of the hat. Distention of the lower edge of the sweat-band would accentuate the curvature of the flange on the leather and a distribution of the surplus length of a slightly overlarge sweat-band would decrease the curvature of the flange. Thus by slightly increasing or decreasing the curvature of the flange or flare at the bottom of a leather sweat-band, the present invention would enable sized sweats being sewn in by machine without variation in the finished product. This is largely possible in the present invention because the

lower edge of the leather band is overseamed to the soft edge of material at the junction of the crown and brim of the hat with the leather in substantially the position it occupies in the finished hat thereby enabling the operative to "drum" it in in the desired manner.

It is to be noticed that the thread of the overedge seam 11 passes through a portion or zone of the anchoring member not occupied by the thread of the stitch 5 which secures the anchoring member to the hat so that the thread of the two seams does not interlace or interengage. This is clearly shown in Fig. 5 of the drawings by the tangential relation of the lines indicating the thread and it will be noticed that the seam 5 passes through the inner layer 7 only of the anchoring member while the seam 11 passes through the outer layer 6 of the anchoring member and also through the fold joining the two layers. And it will also be noticed that the stitches 11 are disposed at an angle to and across the ends of the stitches 5. This is deemed to be a valuable feature of the invention because the needle used to form the overseam 11 will not cut the thread of the uniting seam 5. Over the method employed in hand stitching sweat-bands to a hat this is also a distinct advantage because the threads of the two seams do not interengage or interlace and retain their regular and ornamental appearance unbroken by an interlaced running thread, as in hand sewn sweat bands.

It will thus be seen that I have produced a straw hat by a commercial method permitting stitching with a sewing machine, in the resulting product of which a soft clasp or cushion like grip of the sweat band on the wearer's head is assured. In a given size of hats made by the method disclosed in this invention the sweat-bands will be substantially uniform in size instead of varying appreciably and necessitating retailers' trying several hats on a purchaser to find one that will fit.

Any suitable sewing machine may be used to stitch the anchoring member to the hat and there are a variety of machines on the market suitable for this purpose. To secure the leather to the anchoring member, however, the nice appearing seam 11 may be made in a commercially satisfactory manner on a machine which is illustrated on Sheet 2 of the drawings.

In the machine shown in Fig. 11 the stitch-forming instrumentalities, the needle 20 and the looper 21, as well as the presser-wheel 22, the needle-guard 23, the cord-guide 24 and the sweat-guide 25 are constructed and arranged substantially as described in the patents to Grieb No. 1,206,433, November 28, 1916, and Prazak, No. 939,548, November 9, 1909.

It is desirable to reciprocate the needle 20 in a path which is inclined to the plane defined by the brim of the hat so as to penetrate the soft edge or fold 9 of the anchoring member 4 without breaking the continuity of the keyed thread-loop structures 5 at the junction of the brim and crown of the hat. To this end the head 26 of the machine is canted or inclined as illustrated in Fig. 11, being supported by a vertical standard 27 which is arranged at one end of the base 28, the head 26, standard 27 and base 28 together constituting the frame of the machine and being preferably integral.

The hat is supported when the seam 11 is being made with its brim preferably in a horizontal plane and bottom-side up. The brim of the hat lies upon a work-rest 29 of T-shape in plan view having the free edge of its leg portion 30 curved to conform to the minimum curvature (*i. e.* of greatest radius) of the crown of a hat, a depending flange 31 being provided to furnish an extensive work-engaging surface. This flange 31 cooperates with the periphery of the presser-wheel 22. The work-rest 29 is secured by screws 32 at its opposite ends to a pair of curved arms or levers 33 which are fixedly secured in any suitable manner to a fulcrum shaft 34 located substantially at the junction of the head 26 and vertical standard 27 of the frame. To the forward or free ends of the arms or levers 33 fingers 35 are hinged in any suitable manner with their upper surfaces 36 substantially in the same plane as the upper surface of the work-rest 29 together with which they define a support for the brim of the hat. The fingers 35 are preferably yieldingly held against the crown of the hat by the springs 37. The fingers are preferably spaced an equal distance from and symmetrically with respect to the needle 20. To compel the fingers 35 to move an equal distance in opposite directions when a hat is inserted into (or removed from) the machine, the tail ends 38 of the fingers are joined together by a link 39.

To permit of inserting a hat into the machine the work-rest 29 and fingers 35 carried thereby must be dropped. This is permitted by reason of the fulcrum support 34 at the end of the supporting arms or levers 33. The arms or levers 33 are held in their raised or operative position (shown in Fig. 11 of the drawings) by catches indicated generally by the numeral 40. Each catch comprises a stop or fixed member 41 suitably secured to the frame of the machine and a detent or movable member 42 pivoted intermediately its ends as at 43 to the fixed member. A tension spring 44 yieldingly holds the lower end of a catch 42 beneath an arm or lever 33 and by a chain 45 loosely connected with each of the tail ends of the mov-

able members 42 the arms or levers 33 65 may be conveniently released and lowered. Through the means above described the hat may be supported in a substantially horizontal position bottom-side up with its brim at an angle to the needle-path and may be 70 conveniently introduced into and removed from the machine.

It will be readily apparent that if the hat be rotated while its brim is between the presser-wheel 22 and the depending flange 75 37 of the work rest 29 it will be confined and maintained in angular relation with the needle so that the soft edge or fold 9 only of the anchoring member 4 will be penetrated without piercing or breaking the interlocked or keyed thread-loop structures 5 80 by which the anchoring member has been previously secured to the brim of the hat.

The mechanism for turning the hat comprises a pair of gripping plates 46 having a 85 limited articulation at 47 with levers 48 which are pivoted at 49 to bracket-arms 50 which carry springs 51 engaging extensions 52 of the levers 48 to yieldingly urge the gripping plates 46 against the opposite sides of 90 a hat-crown. These bracket-arms 50 are adjustably secured by screw and slot connections 53 to a block 54 which is hollowed out inside, its internal side walls 55 being disposed in planes intersecting each other 95 at right angles. The hollow block 54 is connected by a species of universal joint to an upright drive shaft 56. The universal joint consists of a knuckle 57 pivoted at 58 to the vertical shaft 56.

The shaft 56 is suitably fixed to a feed-disk 59 which is intermittently rotated by mechanism like that of the above mentioned patent to Prazak, No. 939,548. The feed-disk 59 has an upwardly extending annular 105 flange 60 on which rests an actuating plate 61 cut away at 62 to loosely embrace the drive-shaft 56. At one side of and beneath the plate 61 a pair of blocks 63 are pivotally secured by stud-pins 64. These blocks are 110 arranged on opposite sides of the annular flange 60 which they are adapted to grip when moved in a clockwise direction (as viewed in Fig. 11) but which they do not grip when moved in a counter-clockwise direction. A tension-spring 65 is fixed to the plate 61 as indicated at 66 and also to a part of the frame as indicated. This spring pulls the plate back and keeps the blocks snug against the rim. A dog 68 pivoted at 69 to 120 a fixed arm 70 prevents rotation of the feed-disk in a counter-clockwise direction as viewed in Fig. 11 but permits rotation thereof in the opposite direction being held against flange 60 by spring 71 slightly to 125 one side of the line of centers of pivot 69 and the shaft 56. The plate 61, which may be termed a floating wrench, is operated

from an eccentric 72 on the main-shaft 73 through a series of connections including a pitman 74, a bellcrank 75, a link 76 adjustably connected to a slotted bellcrank 77 which in turn is linked to a rod 78 universally joined at its opposite ends to the before mentioned bellcrank 77 and plate or lever 61.

Preferably but not necessarily a buffer 10 spring 79 is interposed between the top of the knuckle 57 and the block 54. And adjustable stops 80—81 may be provided to hold the work-rest in its lowered position.

The above mentioned machine illustrated 15 in Figs. 11 to 13 inclusive is not herein claimed as part of my invention because it forms a separate and distinct invention constituting subject matter for another application to be filed contemporaneously here- 20 with.

The method and article of this application are not limited in their broadest aspect to straw hats and by the term "straw" as used in the claims it is meant to include all material of a like nature whose character will not permit the stitching of leather sweat bands to the body of the hat, in the manner now employed in stitching sweat bands to soft hats having brims which may be folded, 25 because of the tendency of the material to chip or crack when penetrated by a needle.

It is also to be noted that the external band about the crown of the hat conceals the 30 stitches 5, and also the stitches 8 if they be used, securing the anchoring member 4 to the crown of the hat.

Having thus set forth the nature of the invention, what I claim herein is:

1. A straw hat having a crown and brim, 40 a fold of penetrable material located immediately adjacent the plane of the lower surface of the brim, stitches having a succession of keyed loops holding said fold of penetrable material to the inside junction of 45 the crown and brim portions, more than half of the thread of said stitches being located between the planes of the upper and lower surfaces of the brim so that the fold hugs the inner periphery of the brim, 50 and a sweat band secured by stitches at its lower edge to said fold, the stitches not penetrating the hat, and said two series of 55 stitches being separate and distinct from each other so that the threads of which they are formed are not interlaced.

2. A straw hat having crown and brim portions, a sweat band, and a folded strip 60 of needle pierceable material between the sweat band and the crown of the hat, said strip having thicknesses arranged side by side which are joined by a fold, a series of stitches through the hat and one thickness of the strip only and located close to the fold for making the fold conform to the

inner periphery of the junction of the brim 65 and crown, a second series of stitches through both thicknesses of the strip securing it to the crown only of the hat, and a third series of stitches securing the sweat band to the fold of the strip and not entering the hat 70 body.

3. A straw hat having crown and brim portions, a sweat band, a strip of material between the sweat band and the hat, a row of stitches securing the strip to the hat at 75 the junction of the crown and brim, said strip being folded over and covering said row of stitches, and a second row of stitches securing the lower edge of the sweat band to the fold in the strip. 80

4. A straw hat having crown and brim portions, a sweat band, a strip of material with a soft edge, a series of uniformly spaced keyed-loop structures securing said strip outside of its soft edge to a hat with 85 the soft edge substantially fixed in an accessible position at the junction of the brim and crown, and a second series of stitches securing the lower edge of said sweat band to said soft edge of the strip only. 90

5. A stiff hat having crown and brim portions, a sweat band, a strip of material with a soft penetrable edge, a succession of keyed loop structures securing said strip to the hat with a soft penetratable edge substantially fixed in an accessible position at the junction of the brim and crown, and a second series of keyed loop structures securing the lower edge of the sweat band to the soft penetrable edge of the strip and being 95 separate from and not interlaced with the first-mentioned series of keyed loop structures. 100

6. A straw hat having a crown and brim, a sweat band, an anchoring strip intermediate the sweat band and crown, stitches securing said strip to the hat immediately adjacent the plane of the lower surface of the brim and at the junction of the crown with the brim, and additional stitches securing 110 the sweat band to the strip immediately adjacent the first-mentioned stitches, the two series of stitches mentioned, being formed within separate zones of the material. 105

7. A stiff hat having a sweat band, a strip of fabric folded longitudinally to form inner and outer layers connected adjacent the junction of the crown and brim by a fold, both layers of the strip being arranged between the sweat band and the crown with the 120 inner layer next to the crown and the outer layer next to the sweat band, at least one series of stitches through the inner layer only holding the fold of the strip close to the inside of the hat at the junction of the 125 crown and brim, and a second series of stitches securing the sweat band to the strip, said second series of stitches being disposed

at an angle to and across the ends of the first-mentioned series of stitches, whereby the lower edge of the sweat band may be made to hug the inner periphery of the hat 5 crown and brim at their junction.

8. In the manufacture of straw hats the method of attaching a sweat-band thereto consisting in securing a strip of needle penetrable material to the hat body, positioning the sweat-band within and parallel to the crown of the hat, and subsequently securing the sweat-band to the penetrable material.

9. In the manufacture of straw hats the 15 method of attaching a sweat-band thereto consisting in stitching a piece of penetrable material with a portion thereof accessibly located adjacent the junction of the crown and brim by a series of interengaged thread 20 loops positioning the sweat-band within and parallel to the crown of the hat, and subsequently stitching the sweat-band to the penetrable material with a sewing machine.

10. In the manufacture of straw hats the 25 method of attaching a sweat-band thereto consisting in securing an anchoring member to the body of the hat with a fold of material accessibly located adjacent the inner periphery of the brim, positioning the 30 sweat-band within and parallel to the crown of the hat, and subsequently stitching the lower edge of a sweat-band to the fold of the anchoring member.

11. In the manufacture of straw hats the 35 method of attaching a sweat-band thereto consisting in stitching an anchoring member intermediate its edges to a hat body at the junction of the brim and crown, about the stitching thus made as a hinge folding 40 member back on itself to define a stitch receiving ridge of material, and subsequently stitching the lower edge of a sweat-band to the ridge of the anchoring member.

12. In the manufacture of straw-hats in 45 which the sweat-band is attached to a strip, the method of attaching the strip to the hat which includes stitching the strip to the hat and subsequently folding the strip about and over its securing stitches.

50 13. In the manufacture of straw hats the method of attaching a sweat-band thereto consisting in stitching a single thickness of

an anchoring strip to a portion of a hat, flexing the strip so as to define a fold or bend of material adjacent the junction of the 55 brim and crown, and stitching the lower edge of a sweat-band to the bend or fold in the strip.

14. In the manufacture of straw hats the method of attaching a sweat-band thereto 60 consisting in securing to the hat body a strip of material having a soft edge with said edge at the junction of the brim and crown and by a succession of keyed loop structures, positioning the sweat-band 65 within the hat in substantially concentric relation and parallel with the crown, and subsequently stitching said sweat-band at its lower edge to the soft edge of the strip.

15. In the manufacture of straw hats the 70 method of attaching a sweat-band thereto consisting in forming a strip of material with a soft edge substantially conforming in size to the internal periphery of the brim, stitching said strip to the hat body by a succession of keyed loop structures, the penetrating portions of which structure pass 75 through the strip outside of its soft edge, and subsequently stitching the lower edge of a sweat-band to the soft edge of the strip. 80

16. In the manufacture of straw hats the method of attaching a sweat-band thereto consisting in stitching a strip to a hat, folding the strip intermediate its edges to define a soft accessible edge at the junction of 85 the crown and brim of the hat, again stitching the strip to the hat, positioning a sweat-band within the hat in substantially the position it occupies in the finished article, and subsequently stitching the lower edge of the 90 sweat-band to the soft accessible edge of the strip.

17. In the manufacture of straw hats the method of attaching a sweat-band thereto 95 consisting in reproducing in a straw hat the soft edge condition at the junction of the brim and crown of a soft or felt hat, and subsequently stitching the lower edge only of a leather sweat-band to the soft edge 100 while the sweat-band is in approximately its normal wearing position.

In testimony whereof, I have signed my name to this specification.

RUDOLPH BECKER.
